MARY TURNER, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 14,534, dated January 1, 1884.

Application filed October 27, 1883. Term of patent 3½ years.

To all whom it may concern:

Be it known that I, MARY TURNER, of the city, county, and State of New York, have invented and produced a new and original 5 Design for a Pattern of a Lady's Polonaise with Cape, (numbered 8,959;) and I do hereby declare that the engraved prints accompanying this specification convey to any one accustomed to using paper patterns a clear understanding of how a garment made up by the pattern will appear.

The design exhibits close-fitting fronts showing buttons all the way down, a close-fitting back that has a full drapery at the lower end

of its center seam and is draped by plaits in 15 its side edges, coat-sleeves, a standing collar, and a cape showing gathers, and standing high at the shoulders and having a rolling collar.

What I claim as my invention, and desire to secure by Letters Patent, is—

20

The design for a lady's polonaise with cape, as shown in the engraved prints accompanying this specification.

MARY TURNER.
